Knight & Cook

HIS ATTORNEYS.

UNITED STATES PATENT OFFICE.

JOHN FRIER, OF ST. LOUIS, MISSOURI.

LACING-TIP.

1,318,745.

Specification of Letters Patent. Patented Oct. 14, 1919.

Application filed April 17, 1919. Serial No. 290,669.

To all whom it may concern:

Be it known that I, JOHN FRIER, a citizen of the United States of America, a resident of the city of St. Louis, in the State of Missouri, have invented certain new and useful Improvements in Lacing-Tips, of which the following is a full, clear, and exact description, reference being had to the accompanying drawings, forming a part of this specification.

My invention relates to an improvement in the sheet metal tips commonly applied to the ends of shoe or other laces for the purpose of facilitating the threading of the laces through eyelets and protecting such ends. Lacing tips as commonly made are produced from thin sheets of metal, bent or wrapped around the laces, and unless some provision is made for connecting them to the laces, aside from merely wrapping them therearound, the tips are extremely liable to become detached from the laces after very short usage. The object of my invention is to provide a tip provided with a prong at one of its longitudinal edges by which the lacing may be pierced and around which the body of the tip is wrapped in a manner to clench the prong so that it cannot escape from the position in which it is embedded in the lacing, thereby effectually preventing separation of the tip from the lacing.

Figure I is an elevation of my lacing tip applied to the end portion of a lacing.

Fig. II is a plan view of the lacing tip blank.

Fig. III is a perspective view showing the lacing tip partially applied to the lacing.

Fig. IV is an enlarged cross section through the lacing and the tip thereon.

Fig. V is a cross section illustrating a modified form of wrapping with a tip upon the lacing.

In the drawings, A designates a shoe lacing which may be of any suitable material and which, although shown round in cross section, may be of any other suitable shape.

B designates the blank from which my tip is formed.

The tip comprises a sheet metal body 1 provided at one of its longitudinal or lat-

eral edges with a prong 2 which is adapted to be inserted through the lacing A at a point remote from the end of the lacing which receives the tip, the prong being preferably located near the rear end of the tip body, as shown in the drawings.

In applying the tip blank to the lacing the prong 2 is first passed transversely through the lacing so that its point will extend beyond the lacing to a sufficient degree to permit of its being bent backwardly and clenched onto the lacing, as seen in Fig. III. The body of the tip is thereafter wrapped tightly onto the lacing and onto itself, and during this wrapping operation the clenching of the prong 2 may be performed due to the pressure of the tip body against the projecting end of the prong, or the prong may be bent into clenched position previous to the wrapping operation, as may be found most desirable.

When the wrapping of the tip body around the lacing is performed as contemplated by the illustration Fig. III, the wrapping operation is so carried out that the sheet metal body of the tip is brought first into contact with the prong 2 at the base of the portion of the prong which extends beyond the tip, and thereafter extended along the prong and beyond its point to and overlapping the edge of the tip body through which the prong projects, thereby forming the structure illustrated in cross section, Fig. IV. However, if desired the wrapping may be so performed that the projecting portion of the prong 2 will be bent backwardly relative to the direction of the tip wrapping portion, and as a result the structure shown in cross section in Fig. V will be produced.

I claim:

The combination with a lacing of a sheet metal tip wrapped around said lacing, said tip comprising a body portion and a prong extending from one of the lateral edges of the body through the lacing, and being clenched onto the lacing interiorly of the wrapped tip.

In testimony that I claim the foregoing I hereunto affix my signature.

JOHN FRIER.
